UNITED STATES PATENT OFFICE.

EUGENE EARL NORTON, OF BRIDGEPORT, CONNECTICUT, ASSIGNOR TO JAMES ALBERT WHITMAN, OF NEW YORK, N. Y.

SYNCHRONIZING APPARATUS.

1,190,943.

Specification of Letters Patent. Patented July 11, 1916.

Application filed April 14, 1909. Serial No. 489,931.

To all whom it may concern:

Be it known that I, EUGENE EARL NORTON, a citizen of the United States, and a resident of Bridgeport, in the county of Fairfield and State of Connecticut, have invented certain new and useful Improvements in Synchronizing Apparatus, of which the following is a specification.

This invention relates to a synchronizing apparatus.

The organization of the invention comprises means for reflecting an index mark or numeral of the film of a picture machine to a tell-tale plate adjacent to a moving indicator or rotating dial with index marks or numerals, which indicator or dial is actuated preferably intermittently by the mechanism of a talking machine, so that the two machines are synchronized by maintaining the reflected index mark or numeral and the corresponding index mark or numeral on the dial in proper relation to each other.

In the accompanying drawings, Figure 1 shows a top plan view of a talking machine and a side view of a picture machine with the invention incorporated therewith, Fig. 2 represents a left hand side view of the picture shown in Fig. 1, Fig. 3 shows an enlarged portion of the film or picture record of the picture machine, Fig. 4 is a partial section of Fig. 2 on the line 4, 4, Fig. 5 represents a partial section of Fig. 1 on the line 5, 5, Fig. 6 is an enlarged right hand side view of the talking machine shown in Fig. 1, and Fig. 7 is an enlarged partial section of Fig. 6 on the line 7, 7.

A talking machine is shown with a casing 15, frame plate 16, disk record 17, sound box 40 supporting frame 18, having the side walls 19, 20 and foot 21. A feed screw 22 has its ends journaled in the said side walls, and is connected with the sound box 23 carrying the horn 14, all as shown and described in my patent application for improvements in talking machines, filed April 1, 1909, Serial Number 487,334. A pinion 24 is fastened to one end of the screw 22 and the teeth thereof mesh with the teeth of a driving gear 25 journaled on a pin 26 extending from the side 19 of the frame 18. The gear 25 is rotated by means of the driving mechanism of the talking machine not shown. A pin 30 extending from the side wall 19 of the frame 18 has journaled thereon the

double pinion and gear 31 and 32, the teeth of the said pinion 31 meshing with the teeth of the gear 25. A third pin 35 extending from said side 19 has journaled thereon the double pinions 36, 37, the teeth of the pinion 36 meshing with the teeth of the gear 32. A screw pin 40 extending from the side wall 19 supports the sleeve 41 of insulating material on which is secured the pinion 42, the teeth of which latter mesh with the teeth of pinion 37. A disk 43 is fastened to and extends from a shouldered portion of the sleeve 41, and an adjustable disk 44 is pivoted on the sleeve 41 and has extending from its circumferential surface the pin 45. A washer 46 on the sleeve 41 bears against the disk 44 and a spring 47 extending from said washer bears with its outer portions against the face of the disk 44. The disk 44 can be turned by hand to different positions with respect to the disk 43 constituting a hand regulating device. A washer 48 of insulating material is supported on the sleeve 41, and bears between the body of the spring 47 and the head of screw pin 40.

A block 55 of insulating material extends from the foot 21 of the frame 18 and supports a contact spring 56 which is in the path of the pin 45 extending from the adjusting disk 44. A second contact spring 57 extends from the block 55 and bears against the face of the disks 44.

A picture machine designated by the numeral 60 includes a housing comprising the front wall 61 and side walls 62 and 63. A driving crank 64 with its usual appurtenances propels the picture record 65 having the index numerals 0, 0, &c., 9, 9, &c., on one edge thereof, a numeral being located between a pair of the gripping holes for each picture of the film, each consecutive foot of the film having consecutive numerals, so that there are 16 ones, 16 twos, &c., from 0 to 9, making consecutive groups of numerals.

With the main opening 68 in the front 61 of the picture machine is formed a secondary opening 69, and a swing door 70 is hinged to a cover plate 71 having a main opening 72 and secondary opening 73 which are in alinement respectively with the openings 68 and 69. The door 10 is shown with the hinge pin 70^a having the bent arm 70^b. A sleeve is shown at 70^c connected to a governor 70^d. The sleeve 70^c carries a pul-

ley 70°. A bearing is shown at 70° that carries a rock shaft 70°, and from the latter extend the doors 70^a and 70^b. A rod 70^m extends from the arm 70^a to the bent arm 5 70^b. The rotations of the crank 64, by means of the interposed elements turn the governor and consequently the sleeve 70°. The sleeve 70° by reason of the spreading of the flexible arms of the governor causes the 10 pulley 70^e to move toward the record 65, and thereby the end of the arm 70^b is moved downwardly. At the same time the arm 70^a and the rod 70^m are lowered. The coaction of the rod 70^m and the bent arm 70^b raises 15 the door 70 at a predetermined speed of the record 65. The openings 68 and 72 as usual allow the light rays to fall upon the pictures on the record, and the secondary openings 69 and 73 exposed the numerals on the edge 20 of the record to the light rays. The door 70 swings up when the crank 64 is turned at a predetermined speed.

In the side wall 62 is supported tube 75 with an elbow 76 at one end thereof, and a 25 second elbow 77 at the other end thereof, the axes of the elbows in the present case making angles of 90 degrees with each other. The elbow 76 has its opening 78 opposite the openings 69 and 73 of the picture 30 machine, and a mirror 79 is located in said elbow 76 with its surface at an angle of 45 degrees with the plane of the front wall 61. In the elbow 77 is located a mirror 80 the 35 plane of which makes an angle 45 degrees with the tell-tale plate 81 to be described. A lens 82 is detachably fastened to the end of the elbow 77 by means of a holder 83.

To the side wall 62 and foot of the picture machine is fastened a bracket 84, the vertical member 95 of which contains the slot 40 96. A supporting plate 85 can be secured at different levels to the said vertical member 95 by means of the screws 97. A U-shaped journal bracket with legs 86, 87 and 45 connecting member 88 extends from the supporting plate 85. A spindle 89 is pivoted in the legs 86, 87 and carries on its upper end the dial plate 90 with the numerals 0 to 9 to correspond with the numerals on 50 the film 65. The tell-tale plate 81 is located on the upper leg 86 of the said U-shaped bracket and is adjacent to the circumferential edge of the dial plate 90, so that any numerals which may be reflected on the tell-tale plate 81 can aline with the numeral on the 55 dial plate 90 which may be adjacent thereto. On the spindle 89 are fastened the ratchet wheel 91 with the teeth 92, and the ratchet wheel 93 with the teeth 94. A spring 98 extends from the connecting member 88 of the 60 said U-shaped bracket, and its free end bears on the spindle 89. A spring 99 extends from the same member 88 with its free end located in the path of the teeth 94. 65 Brackets 101 extend from the plate 85 and

support a pin 102 on which latter is pivoted the U-shaped bell crank 103 with the arms 104 and 105. A spring 106 extends between the end of the arm 104 and the plate 85. A screw 107 in threaded engagement with the 70 arm 104 can bear against a post 108 extending from the plate 85, and a screw 109 in threaded engagement with the arm 105 can bear against a post 110 also extending from the plate 85. A magnet 111 extends 75 from the plate 85 and its cores 112 are in the path of the armature 113 carried on the bell crank 103. To the outer end of the arm 105 of the said bell crank 103 is fastened a spring pawl 118 with its hook end 80 119 in the path of the teeth 94 of the ratchet wheel 93. A flexible stop-pawl 120 extends from the bell crank 103 with its hook end 121 in the path of the teeth 92 of the ratchet wheel 91. Binding posts 122, 123 extend 85 and are insulated from the supporting plate 85. A battery 124 has extending therefrom the wires 125 and 126, the wire 125 connects with the binding post 122 and the wire 126 connects with the contact spring 56. A wire 90 127 connects the binding post 123 with the contact spring 57.

To use the invention the operator first turns the dial plate 90 so that the numeral on the film opposite the openings 69 and 73 95 and which is reflected on the plate 81, corresponds with the numeral on said dial plate which is in alinement therewith. He then turns the crank 64 of the picture machine and thereby the record 65 is propelled 100 between the front wall 61 and cover plate 71 in the paths of the openings 68 and 72 and the secondary openings 69 and 73. The rotations of crank 64 swings up the door 70 and thereby the record 65 with its pictures 105 and numerals is exposed to the light rays. While the picture machine is operating, the talking machine is also in operation with its disk record 17 rotating, and the sound box 23 with its appurtenances is traveling across 110 said disk record. The driving gear 25 of the sound box propelling mechanism turning, rotates the double pinion and gear 31, 32, which latter rotate the double pinions 36, 37. The pinion 37 rotates the pinion 42 115 whereby the sleeve 41 with the disk 43 is turned. The disk 44 being in frictional contact with the disk 43 is turned with the latter, and the pin 45 makes contact with the contact spring 56 once during each revolution of the disk 44, which latter rotates in unison with the disk record 17. Each time the pin 45 contacts with the contact spring 56, the electric circuit of the wires 125 and 127 is closed, and thereby excites the magnet 125 111, by virtue of which the cores 112 attract the armature 113 and consequently 120 swings the bell crank 103 on the pin 102. As the arm 105 of the said bell crank descends, the hook end 119 of the spring 125 130

pawl 118 engages one of the teeth 94 of the ratchet wheel 93 and thereby turns the spindle 89 with the dial plate 90 circumferentially the distance for one of the numerals 5 on said dial plate. The flexible stop-pawl 120 with its hook end 121 engaging with one of the teeth 92 of the ratchet wheel 91 controls the amount of the rotation of the dial plate 90. While the film 65 is traveling 10 across the front wall 61, the light rays that pass through the openings 69 and 73 enter the elbow 76 of the tube 75, and by means of the mirrors 79 and 80 are consecutively reflected on the plate 81 which is adjacent to 15 the numerals on the dial plate 90.

To obtain the correct operation of the two machines in other words synchronizing the picture machine with the talking machine, the numerals reflected and seen by the operator 20 on the plate 81, must correspond with the numerals alining therewith on the dial plate 90. In case they do not agree, the operator changes the speed of the picture machine by means of its crank 64 until the 25 numerals on the said plate 81 correspond with their accompanying numerals on the said dial plate 90.

The disk 44 being adjustable to the disk 43 at the beginning of operations the former is turned so that the pin 45 has some 30 distance to travel before making contact with a contact spring 56, so that the dial plate 90 rotates only after a portion of the film 65 has been propelled through the picture machine.

It will be noted that the numerals on the film and dial plate can be varied from those described, using other combination of numbers to synchronize the machines.

Having described my invention, what I desire 40 to secure by Letters Patent and claim is:

1. The combination of means for enabling the movement of a moving picture record and that of a corresponding phonograph record to be synchronized, consisting of a 45 visible indicator driven by the phonograph and means located adjacent the moving picture record and constructed to reflect the image of an indicating mark thereon and 50 display the same in proximity with said visible indicator.

2. In a synchronizing apparatus the combination of means to move a picture record having index marks thereon and a talking 55 machine, a magnet intermittently excited by the talking machine, a dial plate, connections between the latter and said magnet to intermittently rotate the dial plate and means to reflect the said index marks of said record so 60 as to coat with the dial plate.

3. The combination in a synchronizing apparatus for a picture machine and talking machine of means in the picture machine to permit light rays to pass through a portion 65 of the picture record thereof having index

marks, a tube with one end in the path of said light rays, mirrors in said tube to reflect the light rays and said index marks, an intermittently rotated dial plate actuated by the talking machine and located to coat 70 with the reflected index marks of said records.

4. The combination in synchronizing apparatus for a picture machine and talking machine of means in the picture machine to 75 permit light rays to pass through a portion of the picture record thereof during the movement of said record, a tube connected to the picture machine with one end in the path of said light rays, mirrors in said tube 80 to reflect the light rays and index marks located on the record, a tell tale plate opposite the other end of said tube, a dial plate with its circumferential edge adjacent to the tell tale plate, a magnet intermittently excited by the talking machine and connections 85 between the magnet and the dial plate.

5. In a synchronizing apparatus the combination of a talking machine and a picture machine carrying a picture record having 90 index marks, means in the picture machine to permit light rays to pass through a portion of the record with the index marks during the movement of said record, mirrors connected to the picture machine to reflect said light rays, a lens in the path of said rays, a tell tale plate in the path of said rays to exhibit the reflected index marks of the record, a dial plate with its circumferential edge adjacent to the tell tale plate 100 and means actuated by the talking machine to rotate the dial plate.

6. The combination in a synchronizing apparatus for a picture machine having a picture record with index figures adjacent to 105 one edge thereof and a talking machine, means in the picture machine to permit light rays to pass through the portion of the picture record having the index figures during the movement of said record, mirrors connected to the picture machine to reflect said rays, a tell tale plate in the path of said rays to exhibit the reflected index marks of the picture record, a spindle pivoted on the picture machine, a dial plate carried by said 110 spindle with its circumferential edge adjacent to the tell tale plate, a disk journaled on the talking machine and rotated by the mechanism thereof, a pin extending from said disk, an electric magnet connected with the picture machine, a bell crank pivoted over the magnet, an armature for the magnet on the bell crank, a contact spring in the path of the pin of said disk, a second contact spring bearing against said disk, a 115 source of electricity, a wire extending from said source to one pole of the magnet, a second wire extending from said source to the contact spring located in the path of said pin, a third wire connecting the other 120

125 source of electricity, a wire extending from said source to one pole of the magnet, a second wire extending from said source to the contact spring located in the path of said pin, a third wire connecting the other 130

4
pole of the magnet and the second contact spring, a ratchet wheel fastened to the spindle of the dial plate, a spring pawl extending from said bell crank in the path of the 5 teeth of said ratchet wheel to intermittently rotate said spindle and thereby the said dial plate.

7. The combination in a synchronizing apparatus for a picture machine having a picture record with a series of consecutive 10 groups of numerals, one of said numerals for each picture of the record, a dial plate on the picture machine intermittently rotated in connection with the mechanism of a talking 15 machine and means to exhibit the numerals of said record adjacent to said dial plate.

8. The combination in a synchronizing ap-

paratus for a picture machine having a picture record with index marks and a talking 20 machine, an adjustable disk rotated by the mechanism of the talking machine, a magnet connected with the picture machine, a dial plate operated by said magnet, an electric circuit connecting the magnet and adjustable disk, means to intermittently break 25 said circuit and means to reflect said index marks adjacent to said dial plate.

Signed in the borough of Manhattan, in the county of New York and State of New 30 York, this 10th day of April, A. D. 1909.
